EDMUND MASTERS IVENS, OF NEW ORLEANS, LOUISIANA.

PLATE-VALVE

1,197,936.

Specification of Letters Patent. Patented Sept. 12, 1916.

Application filed February 8, 1916. Serial No. 77,076.

To all whom it may concern:

Be it known that I, EDMUND M. IVENS, residing at New Orleans, in the parish of Orleans and State of Louisiana, have invented certain new and useful Improvements in Plate-Valves, of which the following is a specification.

This invention has reference to improvements in that type of valves used in the compressing cylinders of air, gas and ammonia compressors, blowing engines and dry vacuum pumps, and my invention primarily has for its object to provide a simple, economical and stable construction of valve of the general type stated, that may be used for either the inlet or the discharge, by simply reversing the position.

Another object of my invention is to provide a plate valve having the coöperating parts formed for effecting a gradual seating of the valve from the center to the ends to thereby overcome fluttering and destructive hammering or clatter.

Again, my invention comprehends an improved construction of plate valve, having a large port area and operating under a low lift, and of sufficient lightness to reduce the resistance of the passage of the air or gas to the minimum, and which is also operable under such quick closure action that prevents losses due to return of gas or air.

With further objects in view that will hereinafter appear, my invention is an improved plate valve that embodies the peculiar construction and novel arrangement of the parts hereinafter described in detail, specifically pointed out in the appended claims and illustrated in the accompanying drawings, in which:

Figure 1 is a top plan view of the valve plate proper. Fig. 2 is an edge elevation thereof. Fig. 3 is a top plan view of the valve cover or keeper. Fig. 4 is an elevation thereof. Figs. 5 and 6 are respectively cross sections on the lines 5—5 and 6—6 on Fig. 3. Fig. 7 is a top plan of the valve seat. Fig. 8 is a view of the bottom side of the said seat. Figs. 9 and 10 are respectively cross sections on the lines 9—9 and 10—10 on Fig. 7. Fig. 11 is a cross section of the complete valve taken on the line 11—11 on Fig. 13, the means for holding the valve in its position in the cylinder being shown as operatively connected with the said valve.

Fig. 12 is a side elevation of the valve, locking in the direction of the arrow e, on Fig.

13. Fig. 13 is a cross section of the valve on the line 13—13 on Fig. 11. Fig. 14 is a cross section of a modified form of my valve mechanism. Fig. 15 is a plan view of the form of valve plate embodied in the modified construction. Fig. 16 is a sectional elevation of a compressor with my valve mechanism operatively applied.

In the drawings, 1 indicates a portion of a working cylinder in which my improved plate valve mechanism is operatively applied, and 2 indicates a portion of the working piston.

3 designates the valve proper which in my construction is in the nature of a thin clock spring metal plate and the said plate has a series of serrated uniformly spaced transversely disposed ribs separated by parallel slots, the ribs forming closure members 4 for closing the ports 40 in the valve seat, best shown in Fig. 13, and the said plate also includes solid bridge portions 5 at the diametrically opposite rims that serve as closure or cover members for supplemental rim ports 41 at diametrically opposite points of the valve seat that communicate with all of the transverse ports 40 at their respective sides, as shown.

In practice, the rib members of the valve 85 are ground to a perfect seat outside, and are made thinner at the middle (as at 6) than at the ends to allow each portion of the valve plate to conform to the inclined seat surfaces provided therefor as will presently be further explained.

As is best shown in Fig. 7, the body 16 of the valve seat includes a solid bridge-like portion 17 that extends across and separates the two sets of ports or fluid passages 40—40, and the outer peripheral edge of the body has a groove 18 to form a gasket joint, or it may be grooved for a proper fitting onto the cylinder 1. The body portion 16 also includes an axial hub for receiving the 100 clamp or binding bolt, and the two sets of passages or ports 40—41 have their edges rounded to permit a maximum free access and egress of the air or gas with minimum friction losses.

7 designates, what I term the valve cover or keeper, and the same is shown in detail in Figs. 3, 4, 5 and 6, and in practice, the said cover is preferably of semi-steel and includes an axial opening for receiving the 110 binding bolt 9 and at diametrically opposite sides it has pendent portions 10 that serve as

abutments for the free ends of the valve plate, as a whole, and to limit the distance between the valve cover and the valve seat for determining the lift of the valve. The 5 cover 7 includes a bridge portion 70 that extends transversely of the ports 40 in the valve seat and in the under face thereof it has transverse guide grooves 12, one for each rib or closure member of the valve and the 10 said grooves 12, when the parts that constitute my complete valve structure are assembled, oppose the like guide grooves 20 in the bridge portion 17 of the valve seat 16. By forming the opposing bridge portions of the 15 cover 7 and the seat 16 with guide grooves, as stated, the valve plate, as a whole, is guided to the valve seat the same as is each individual rib portion of such valve.

The valve seat, as shown, is on a gradual 20 and uniform incline downwardly from the axial aperture to the peripheral edge thereof, as is clearly illustrated in Fig. 11 which shows that the guide grooves in the bridge portion of the seat 16 are tapered on an incline the same as the incline of the seat and that the cross guides 12 in the bridge portion 25 of the cover are inclined upwardly with the degree of incline the same as that of the incline of the guide grooves 20 in the valve 30 seat.

By reason of forming the opposing sets of 35 guide grooves 12-20 in the manner stated and shown causes the cover or keeper to engage the valve plate and clamp it down onto the valve seat at the center thereof only, it being understood that the valve plate is thus 40 clamped between the bridge portions of the cover and the seat the full width thereof, see Fig. 13, and since the depth of the guide 45 grooves 12 and 20 gradually increase toward the outer edges of the said bridge portions, it follows, that in operation the body of the valve is free to lift from its central clamped point to the outer edge and at the same time 50 maintain a relatively flat condition at points between the peripheral edge and central fixedly held end, it being apparent that in moving to the seat the valve is guided as a whole as the rib portions, from the center to the outer edge, are successively guided to 55 their seats.

14-14 designate a number of spiral 60 springs, four being shown that seat within sockets 15 in the valve cover and which rest 55 against the rim portion of the valve and serve to bend the said plate down onto the inclined valve seat, and it should be stated that the tension of the several springs 14, in practice, is only slightly greater than the 65 resistance offered by the bending valve plate.

The rib portions of the valve plate are made thinner at the middle than at the ends, as before stated, to provide for permitting the ribs to readily conform to their respective inclined groove seats before mentioned.

22 designate dowel pins that project from the hub portion of the valve seat adapted for passing through the apertures 23 in the valve plate and for entering sockets 24 in the cover plate and thereby serve to hold the 70 valve plate against lateral displacement. As the valve seat is inclined as stated, the tension of the bent valve will serve to assist in the lifting, since the only resistance offered to the passing of the elastic fluid will be the 75 difference between the said tension and the coil spring tension, plus the resistance offered by the unbalanced seating area. While I prefer to use an inclined valve seat, such shape of seat is not essential to the successful 80 operation of my valve. The seat may be flat and when thus, at least two of the coiled springs 14 may be dispensed with. The edges of the ports are slightly raised, as shown, to obtain tight seating and reduce 85 the unbalanced area of seating.

Figs. 14 and 15 illustrate a slightly modified form of my valve mechanism and the same includes a valve plate designed as shown in detail in Fig. 15, which shows the 90 ribs 45 held together at the middle of the plate instead of at the outer ends, as in the other form of valve shown in Fig. 1. In the said modified form, the valve seat structure and the valve keeper remain the same, except that the seat is without the circular ports 41 that appear in the other valve structure stated. The face of the seat in the modified form is flat and the spiral springs 14 found in the other valve devices described 100 are eliminated.

The manner in which my valve mechanism is operatively applied is clearly shown in Figs. 16 and 11 which also illustrate means for holding the valve to its position for co-operation with the working cylinder and the piston of the compressor. As shown, the means for holding the valve comprises a screw shank F that operates through the 105 threaded passage in a cover plate " whose upper end terminates in a wrench head D, and carries a lock nut C. The lower end of shank F terminates in a socket f formed with an internal thread f' for receiving a 110 centrally apertured threaded plug B. A collar A is held within the socket f by the plug B and it is attached to the upper end of a plunger rod E, by a left hand thread connection e and a countersunk set screw e', as shown. Lower end of the rod E forms 115 the binding post 9 which includes a bead 90 at the lower end that engages the under side of the hub of the valve seat, and a threaded portion 91 to receive lock and jam nuts 92-92 that hold the valve members clamped in proper operative condition.

By reason of the peculiar construction of the means for holding the valve in operative position, as described and shown, it is apparent by loosening the jam nut C and turn-

ing the shank head D clockwise, the valve is forced straight ahead into its proper position in the valve chamber that communicates with the working cylinder (see Fig. 16) or 5 by turning the shank head D counterclockwise the valve can be readily drawn straightway outward, it being understood that the valve and the link rod do not rotate either in placing or removing the valve, the result, 10 when operating the shank head D, as stated, being a uniform and tight seating of the valve at the shoulders n—n and as easy and quick withdrawal of said valve when occasion demands. The latter operation (after 15 the compressor has operated for some time) is the more difficult, hence a left thread is cut in the collar A so that the turning of the shank will tend to tighten the collar onto the member E.

20 My invention, as described and shown, is applicable as a compressor inlet or discharge valve, and while the present showing and description discloses certain preferred details of structure, it is understood that the 25 said details may be modified or varied to suit the specific requirements in the practical application of my valve, without departing from the scope of the invention set out in the claims.

30 My construction of valve, by reason of its sensitive setting, is adapted for working with great rapidity and positiveness of action and without danger of injurious noises or shocks.

35 What I claim is:

1. In a valve structure, a valve seat having a set of ports arranged in grid-like form and including a transverse member having guide grooves, a valve disk fitted over said 40 valve seat and having portions to lie in said guide grooves, and a valve cover fitted over the aforesaid structure and including a member having guide grooves to cooperate with the aforesaid guide grooves.

45 2. In a valve mechanism, a valve seat having two sets of parallelly arranged port slots connected by annular slot sections, said seat including a transverse partition between said sets of port slots, a single valve disk of 50 grid-like form for closing all of said slots, means for securing said disk on said valve seat along said transverse partition whereby each half of said disk may have independent flexure.

55 3. In a valve mechanism for fluid compressors comprising a valve seat having two sets of parallel ports divided by a bridge portion, the said bridge portion having transverse guide grooves in its upper face 60 that align the two sets of ports and a centrally apertured hub, a spring plate having alternate slots and ribs and a central aperture, the ribs forming closure members for fitting over the two sets of ports, a cover 65 including an apertured hub and a bridge

portion for fitting over the hub and the bridge portion of the valve seat, the said cover bridge portion, having transverse guide grooves that register with like grooves in the valve seat, the ribs of the valve plate 70 fitting between the two sets of guide grooves and a clamp bolt connection mounted in the hubs of the valve seat and the cover.

4. In a valve mechanism for fluid compressors comprising a valve seat having two sets of parallel ports divided by a bridge portion, the said bridge portion having transverse guide grooves in its upper face that align the two sets of ports and a centrally apertured hub, a spring plate having 75 alternate slots and ribs and a central aperture, the ribs forming closure members for fitting over the two sets of ports, a cover including an apertured hub and a bridge portion for fitting over the hub and the bridge 80 portion of the valve seat, the said cover bridge portion having transverse guide grooves that register with like grooves in the valve seat, the ribs of the valve plate fitting between the two sets of guide grooves, 85 a clamp bolt connection mounted in the hubs of the valve seat and the cover, and means for securing the valve plate against lateral displacement.

5. In a valve mechanism for fluid compressors comprising a valve seat having two sets of parallel ports divided by a bridge portion, the said bridge portion having transverse guide grooves in its upper face that align the two sets of ports and a centrally apertured hub, a spring plate having 90 alternate slots and ribs and a central aperture, the ribs forming closure members for fitting over the two sets of ports, a cover including an apertured hub and a bridge portion for fitting over the hub and the bridge portion of the valve seat, the said cover bridge portion having transverse guide 95 grooves that register with like grooves in the valve seat, the ribs of the valve plate fitting 100 between the two sets of guide grooves, a clamp bolt connection mounted in the hubs of the valve seat and the cover, the said cover including stop portions adapted for being engaged by the opposite outer portions 105 of the valve plate to limit the lift of said plate.

6. In a valve mechanism of the character stated, a centrally apertured valve seat, the said seat having two distinct sets of air 120 ports and a bridge portion that extends transversely of and between the two sets of ports, a centrally apertured spring plate mounted over the valve seat, said plate having alternate slots and ribs, the latter forming closures for the two sets of ports in the seat, a centrally apertured cover including a transverse bridge portion for fitting over the bridge portion of the valve seat, the opposing faces of the bridge portions of the 125 130

valve and the cover having transverse guide grooves that aline the ports in the valve seat and receive the ribs of the valve plate, the said grooves being shaped whereby to clamp the valve plate at the mid line only and means for clamping the cover onto the valve plate and the valve seat.

7. In a valve mechanism of the character stated, a centrally apertured seat having two sets of parallel fluid ports, and a bridge portion that extends transversely of and between the two sets of ports, the valve engaging face of the said seat being downwardly inclined in opposite directions from the bridge portion, a spring grid-like plate valve mounted over the valve seat and having a central aperture, the transverse ribs of the said plate extending entirely across and forming closures for the two sets of ports in the valve seat, a centrally apertured cover that includes a bridge portion for opposing the bridge portion of the valve seat, said cover and valve seat bridge portions having registering transverse guide grooves that aline the opposite sets of ports in the valve seat, the grooves in the valve seat being inclined in the plane of the valve seat inclines, the grooves in the bridge portion of the cover being inclined upwardly, the degree of inclination thereof being like that of the incline of the valve seat guide grooves whereby to grip the valve plate along a transverse mid line, the ribs of the valve plate fitting the said opposing grooves and means for clamping the cover, the plate and the said seat together.

8. In a valve mechanism of the character stated, a centrally apertured seat having two sets of parallel ports, and a bridge portion that extends transversely of and between the two sets of ports, the valve engaging face of the said seat being downwardly inclined in opposite directions from the bridge portion, a spring grid-like plate valve mounted over the valve seat and having a central aperture, the transverse ribs of the said plate extending entirely across and forming closures for the two sets of ports in the valve seat, a centrally apertured cover that includes a bridge portion for opposing the bridge portion of the valve seat, said cover and valve seat bridge portions having registering transverse guide grooves that aline the opposite sets of ports in the valve seat, the grooves in the valve seat being inclined in the plane of the valve seat inclines, the grooves in the bridge portion of the cover being inclined upwardly, the degree of inclination thereof being like that of the incline of the valve seat guide grooves whereby to grip the valve plate along a transverse mid line, the ribs of the valve plate fitting the said opposing grooves, means for clamping the cover, the plate and the said seat together, the said cover in-

cluding stop portions that fit over the opposite outer ends of the valve seat to limit the lift of the valve plate.

9. In a valve mechanism of the character stated, a centrally apertured seat having two sets of parallel ports, and a bridge portion that extends transversely of and between the two sets of ports, the valve engaging face of the said seat being downwardly inclined in opposite directions from the bridge portion, a spring grid-like plate valve mounted over the valve seat and having a central aperture, the transverse ribs of the said plate extending entirely across and forming closures for the two sets of ports in the valve seat, a centrally apertured cover that includes a bridge portion for opposing the bridge portion of the valve seat, said cover and valve seat bridge portions having registering transverse guide grooves that aline the opposite sets of ports in the valve seat, the grooves in the valve seat being inclined in the plane of the valve seat inclines, the grooves in the bridge portion of the cover being inclined upwardly, the degree of inclination thereof being like that of the incline of the valve seat guide grooves whereby to grip the valve plate along a transverse midline, the ribs of the valve plate fitting the said opposing grooves, means for clamping the cover, the plate and said seat together, the said cover including stop portions that fit over the opposite outer ends of the valve seat to limit the lift of the valve plate, and springs mounted on the cover that engage the valve plate to bend the valve plate down onto the inclined surfaces of the valve seat.

10. In a valve mechanism for compressors of the character described, and which includes a working cylinder having a valve chamber formed with a seat, and a cover for closing said chamber; of a valve seat and valve movable in the chamber to close against the seat in the chamber, means for moving the valve seat and valve within the chamber to the operative or inoperative positions, said means comprising a threaded shank that operates through the valve chamber cover, a rod that extends from the valve and a swivel connection that joins the rod and the threaded shank.

11. In a valve mechanism for compressors of the character described, and which includes a working cylinder having a valve chamber formed with a seat, and a cover for closing said chamber; of a valve seat and valve movable in the chamber to close against the seat in the chamber, means for moving the valve seat and valve within the chamber to the operative or inoperative positions, said means comprising a threaded shank that operates through the valve chamber cover, a rod that extends from the valve, a swivel connection that joins the rod and

the threaded shank, said connection comprising a socket on the threaded shank, an apertured plug that fits in and forms a closure for the socket and through which 5 the valve rod passes, and a disk in the socket connected to the upper end of the rod.

12. In a valve mechanism for compressors of the character described, and which 10 includes a working cylinder having a valve chamber formed with a seat, and a cover for closing said chamber; of a valve seat and valve movable in the chamber to close against the seat in the chamber, means for

moving the valve seat and valve within the 15 chamber to the operative or inoperative positions, said means comprising a threaded shank that operates through the valve chamber cover, a rod that extends from the valve, a swivel connection that joins the rod and 20 the threaded shank, said connection comprising a socket on the threaded shank, an apertured plug that fits in and forms a closure for the socket and through which the valve rod passes, and a disk within the 25 socket joined to the rod by a left hand threaded connection.

EDMUND MASTERS IVENS.
